Primary Examiner — George D. Kirschbaum
Assistant Examiner — Kendra Leslie Hamilton(57) **CLAIM**

The ornamental design for a lid for a beverage container, as shown and described.

DESCRIPTION

FIG. 1 is a front, top perspective view of a lid for a beverage container showing our new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dash-dash broken lines throughout the drawing figures depict portions of the lid for a beverage container that form no part of the claimed design. The broken lines and unshaded surfaces bounded by broken lines form no part of the claimed design.
